UNITED STATES PATENT OFFICE

WILLIAM WARD DAVIDSON, OF EVANSTON, ILLINOIS, ASSIGNOR TO DAVIDSON MANUFACTURING COMPANY, OF MADISON, WISCONSIN, A CORPORATION OF WISCONSIN

FEEDING MECHANISM

Application filed July 23, 1927. Serial No. 207,934.

This invention relates to machines for separating and feeding blanks, particularly cards, envelopes and the like.

My improved machine is particularly designed and adapted for feeding blanks, as cards and envelopes, to an addressing machine and for ejecting them therefrom, and a principal object of the invention is to provide a machine for this purpose, which will be simple in construction, efficient and dependable in operation, and which is readily adaptable for feeding blanks of different finish and stiffness.

Other objects of the invention will appear hereinafter.

15 A blank feeding machine embodying my invention and improvements comprises the various features, combinations of features and details of construction hereinafter described and claimed.

20 In the accompanying drawings in which my invention is fully illustrated,

Fig. 1 is a top plan view of a feeding mechanism embodying my invention and improvements, shown in conjunction with the co-operating parts of an automatic addressing machine;

Fig. 2 a vertical section taken substantially on line 2—2 of Fig. 1;

Fig. 2^a an enlarged detail section taken substantially on line 2^a—2^a of Fig. 1;

Fig. 3 a section taken substantially on line 3—3 of Fig. 1;

Fig. 4 is an enlarged detail sectional view, substantially on the line 4—4 of Fig. 1, showing means for actuating the separator roll shaft, a ratchet gear forming part thereof being omitted;

Fig. 5 is an enlarged fragmentary detail sectional view, substantially on the line 5—5 of Fig. 1, showing the means for actuating the separator roll shaft and including said ratchet gear;

Fig. 6 a sectional elevation taken substantially on line 6—6 of Fig. 1; and

Fig. 7 a sectional elevation taken substantially on line 7—7 of Fig. 1.

The preferred form of construction as illustrated in the drawings comprises a suitable table 10 having stencil guides 11 extending

transversely thereof. A vertically reciprocating platen or pressure plate 12 is mounted centrally on the table 10 below the stencil guides 11 and provided with a cam roller 13 riding upon the periphery of a cam arm 14 fixed to a rocker shaft 15 mounted under the table 10, as best shown in Fig. 2. The rocker shaft 15 is operated by means of a rocker arm 16 thereon connected by a link 17 with the drive shaft of the addressing machine which thus operates to periodically rock the shaft 15 and consequently elevate and depress the platen or pressure plate 12.

55 Stencils 18 are automatically fed through the guides 11 by the normal operation of the addressing machine.

Co-operating with the stencils 18 and the platen 12 is a combined pressure and inking roll 19 mounted on one arm 20 of a bell crank lever, the other arm 21 of which is connected by a bolt 22 with one end of a link 23, in turn connected with the rocker arm 16, as shown. The roll 19 co-operates with an inking roll 24 of the addressing machine.

70 The mechanism heretofore described are parts of an automatic addressing or stencil-ing machine, operating in the usual way to automatically imprint addresses from the stencils 18 on envelopes or other blanks placed under said stencil guides. Said mech-75 anism forms no part of the present invention, except in so far as the same co-operates with the mechanism to be presently described.

The rocker shaft 15 carries a pair of rocker arms 25 pivotally connected with the ends of bent links 26 having notches 27 interchangeably engaging bolts 28 on depending lugs 29 on a reciprocating carriage 30.

The reciprocating carriage 30 is mounted to reciprocate on rollers 31 running in slots 32 in suitable guide bars 33 having securing flanges 33' secured to the table 10, said carriage 30 being thereby mounted to reciprocate toward and from the stenciled guides, above described. The notches 27 permit of adjustments of the carriage 30 to vary the points at which the carriage stops on its approach to the stencil guides.

90 A pack box or receptacle 34 is mounted on the carriage 30 at a forward and downward 95 100

inclination as indicated, the bottom of said receptacle being extended at 35 at the lower end of the receptacle to constitute a guide for the blanks 36 as they are fed from the receptacle. For convenience said plate may be 5 designated the separator plate. The blanks 36 are supported in said receptacle in edge-wise position and at a tilt or angle, as shown. With reference to the separator plate, which 10 forms the bottom of the receptacle 34. A gauge bar 37 is arranged to contact with the upper edges of the blanks 36 to hold them in such tilted positions, weights 36' being slidably mounted on the edges of the inclined 15 sides of the receptacle 34 to normally advance the pack of blanks 33 downwardly in the receptacle.

The gauge bar 37 is carried by a vertical bar 38 slidably against a supporting bar 39 20 and adapted to be adjustably clamped thereto by the clamp 40, said supporting bar 39 being mounted on a transverse bar 41 of the carriage 30.

By this arrangement it will be noted that 25 the gauge bar 37 may be independently adjusted to vary the tilt of the pack of envelopes 36 or to suit different sizes of envelopes.

It will also be noted that the gauge bar 30 37 is arranged at a slight inclination to the top edges of the pack of envelopes 36, which inclination facilitates feeding of the envelopes downwardly in the receptacle and insures uniform positioning of the endmost envelope in the pack.

A separator roll 42 in the form of two roller sections is mounted on a transverse shaft 43 projecting through slots 44 in the sides of the carriage 30. As best shown in 40 Fig. 1, the shaft 43 at one end has bearings in rocker arms 45 and at the other end in a single rocker arm 45', said mounting permitting of independent adjustment of the separator roller 42 toward and from the separator plate 35. The rocker arms 45 and 45' 45 are fixed to a transverse rocker shaft 46 carrying an operating arm 47 connected with an adjusting screw 48, as best shown in Fig. 6, whereby the positions of the separator roller 50 42 may be adjusted as desired.

Intermittent rotation in a direction to project blanks 36 from the pack box 34, indicated by the arrows in Figs. 3 and 4, is adapted to be imparted to the separator roll shaft 55 43 by means as follows (see particularly Figs. 1, 4 and 5):

Mounted on the separator roll shaft 43, so as to turn freely thereon, are a ratchet wheel 49 and a gear or pinion 50, said ratchet wheel 60 and gear being connected so as to turn together. Also, secured to said separator roll shaft 43, so as to rotate therewith, is a disk 52, pivoted to which are pawls 51 which are 65 adapted to engage the teeth of the ratchet wheel 49 and are maintained yieldingly in

engagement therewith by springs 51', in a usual manner. Pivotally connected at 55 to a post 56 on the table 10 is a rack bar 54, the teeth of which are maintained in engagement with the teeth of the gear or pinion 50 70 by a yoke-shaped bracket 53 mounted to turn freely on the separator roll shaft 43, to which said rack bar 54 is slidably fitted, thus permitting the gear or pinion 50 and associated parts to move freely lengthwise of said rack 75 bar.

With the described construction, it is obvious that, as the carriage 30 reciprocates in operation, the rack bar 54, through its engagement with the gear or pinion 50, will impart rotation to said gear or pinion in opposite direction, and that, with the relation shown (see particularly Fig. 5), rotation of said gear corresponding to movement of the carriage 30 away from the stencil guides 11 80 85 will cause the teeth of the ratchet wheel 49 to engage the pawls 51 pivoted to the disk 52, thereby imparting rotation to said disk 52, the separator roll shaft 43 to which said disk is secured, and to the separator roll 42 secured to said shaft, with said gear or pinion 50, in a direction to advance a blank in the pack box, resting in contact with the separator roll 42 so that it will project at the forward end of the pack box beyond the end 90 of the separator plate 35, as shown in Fig. 2.

On the forward movement of the carriage, that is, its movement toward the stencil guides 11, the spring pawls 51 will run freely over the teeth of the ratchet wheel 49, thus permitting idle movement of the gear or pinion 50 under the influence of the rack bar 54.

Co-operating with the separator roll 42 are lower and upper pull-out rolls 57 and 59 secured to shafts 58 and 60, respectively, the 105 relation being such that, when the carriage 30 is at the limit of its forward movement, that is, of its movement toward the stencil guides 11, the front end of the blank 36 which has been advanced by the separator roll 42 on the preceding rearward stroke of the carriage 30, as explained, will be between the pull-out rolls 57 and 59 and in position for engagement by said pull-out rolls.

The shaft 60 is mounted at each end in bearing blocks 61 vertically slidable in slots 62 on the sides of the carriage 30 and normally held depressed with the upper pull-out roll 59 in contact with the lower pull-out roll 57, by means of compression springs 63, as 115 best shown in Fig. 6. The lower shaft 58 is extended at one end and is provided with a grooved pulley 64, as best shown in Fig. 1, adjusted to which is a constantly driven belt, not shown, whereby said shaft 58 and the lower pull-out roll 57 are constantly driven in the direction of the arrow on Fig. 3, as 120 will be readily understood.

By this arrangement the pull-out roll sections 59 are normally held in operative con- 130

tact with the lower pull-out roll 57, as will be readily understood.

Longitudinal cam bars 65 are mounted at their rearward ends on supporting brackets 66 on the guide bars 33, said cam bars being set to constitute tracks for rollers 67 on the shaft 60, said tracks being set at such an elevation that when the rollers 67 are resting thereon the roller sections 59 are raised out of contact with the roller 57, but when the rollers 67 run off from the forward ends of the tracks 65, the roller sections 59 are depressed by the springs 63 into operative contact with the co-operating lower pull-out roller 57 to engage a blank delivered between said pull-out rollers by the separator roll 42, forcibly advancing the same into the addressing mechanism. The length of the cam bars 65 is such that the roller sections 59 are held elevated during the time when the front blank is being fed by the separator roll 42 as above described, during the rearward movement of the carriage 30 but toward the end of the forward movement of said carriage, said rollers 67 run off from the forward ends of the track 65 with the effect on the separated blank above described.

A bent guide plate 68 is arranged between the pull-out rollers 57 and 59 to guide the blanks 36 being fed by the pull-out rollers to proper position under the stencil guides 11, as indicated in Fig. 3. The guide plate 68 is supported by bars 69 which depend from a transverse bar 70 on the carriage 30, as indicated.

The pull-out rollers and the guide plate 68 are so positioned with reference to the gauge 71 of the addressing machine that the blanks 36 are advanced thereby into contact with the gauge 71, which is set to properly position said blanks for printing by the addressing machine, as will be readily understood by those skilled in the art.

The operation of the parts is so timed that a blank will be thus fed into position between the pressure roller 19 and the platen 12 of the addressing machine as to receive the proper impression from the proper stencil 18, as will be readily understood.

The gauge 71 is carried by an arm 72 having a longitudinal slot 73, slidably fitted to fixed guide member 74 being connected by a rod 75 with a reciprocating bracket 76 mounted at the edge of the table 10, as shown.

The bracket 76 carries a roller 77 contacting with a star wheel 78 on a shaft 79. The shaft 79 carries a ratchet 80 co-operating with a ratchet arm 81 carrying a spring pawl 82.

The ratchet arm 81 is connected by a rod 82 with stud 83 pivoted on the rocker arm 16, the rod 82 sliding freely through said stud and being provided with stop shoulders 84 as indicated.

A tension spring 85 is connected, as shown, with the bracket 76 for normally holding said

bracket and said gauge 71 in retracted positions, the construction being such that immediately after each blank is addressed, as above described, the gauge 71 is quickly thrown forward to kick or project an addressed blank out from under the stencil guides 11 along the top of the table 10 and beneath the lower pull-out roller 57, which is positioned above and in such close proximity to the table top that it will engage blanks thus delivered beneath it, and eject them from the machine into a suitable rack 86 provided for the purpose. It will thus be seen that each blank from the pack in the receptacle 34 will be individually fed into the addressing or stenciling machine 80 and automatically ejected therefrom.

In the preferable construction shown, an idle roll 87—for convenient reference designated the ejector roll—is mounted to co-operate with the driven pull-out roll 57, being positioned at the opposite side of said pull-out roll from the pull-out roll 59. Said ejector roll is secured to a shaft 88 mounted so that said roll will be freely movable towards and from the pull-out roll 57, and is maintained 90 normally, yieldingly in contact therewith by springs applied thereto, all substantially in the same manner as the pull-out roll 59. Also, like said pull-out roll 59, the ejector roll preferably comprises a plurality of sections which are separately adjustable lengthwise of the shaft 88, that is transversely of the machine.

The device may be readily adjusted to various kinds and sizes of blanks by adjusting the gauge bar 71 relatively to the separator plate, the tilt at which the blanks 36 are held being varied for blanks of various materials and degrees of stiffness and finish, their inclination being varied towards the horizontal 105 for separating thicker and stiffer blanks and towards the vertical for thinner and more flexible blanks. Likewise, the separator roller 42 may also be independently adjusted relatively to the separator plate, thus providing 110 a further adjustment to adapt the machine for separating blanks of varying qualities and stiffness of material.

An important feature of my improved blank separating and feed machine resides 115 in so positioning the gauge or stop 71, when retracted, and the pull-out roller 57, when fully advanced, and in so proportioning said pull-out roller 57, that the distance between the gauge bar 71 when in normal position, and the proximate side of the pull-out roll 57 will be slightly less than the length of the blanks, so that as fed and when in printing position—defined by the gauge 71—the rear ends of the blanks will rest against the side of said pull-out roll proximate said gauge bar in such relation that rotation of said pull-out roll will flick the end of the blank around said roll so that the blank will rest flat upon the table top 10.

Also, to insure engagement of the rear end of said blank with the pull-out roll so that it will be flicked around said pull-out roll, said roll preferably is provided with lengthwise corrugations 89 with which the ends of the blanks will engage as said roll rotates, and be carried downward onto the table 10, as stated.

The mechanism disclosed will operate with great efficiency and accuracy in feeding and ejecting blanks.

The specific form and arrangement of parts disclosed is a simple and effective one for the purpose.

While I have illustrated and described the preferred form of construction for carrying my invention into effect, this is capable of variation and modification without departing from the spirit of the invention. I, therefore, do not wish to be limited to the precise details set forth, but desire to avail myself of such variations and modifications as fall within the scope of the appended claims.

I claim:

1. In a machine for separating and feeding blanks, the combination of a blank receptacle, blank separating means comprising a separator plate which forms the bottom of the blank receptacle, a separator roll mounted in said blank receptacle, means for supporting blanks in edgewise positions on the separator plate with the front blank in contact with the separator roll, means for advancing the blanks towards said separator roll, means for imparting rotation to said separator roll, pull-out rolls mounted to move toward and away from each other and in association with the blank separating means, and means for imparting said movements to said pull-out rolls.

2. In a machine for separating and feeding blanks, the combination of a blank receptacle, blank separating means comprising a separator plate which forms the bottom of the blank receptacle, a separator roll mounted in said blank receptacle, means for supporting blanks in edgewise positions on the separator plate with the front blank in contact with the separator roll, means for advancing the blanks towards said separator roll, means for imparting rotation to said separator roll, pull-out rolls to receive said projected blanks, means for continuously driving one of said pull-out rolls, an idle roll movable towards and away from said continuously driven roll and adapted to be actuated intermittently by contact therewith, and means for imparting movement to said idle roll towards and away from said driven roll.

3. In combination, a machine for separating blanks, a stop which defines the position of the blanks in the machine, said stop being movably supported, blank separating means, pull-out rolls mounted in position to receive blanks therefrom and to advance them into contact with the stop which defines the posi-

tion of the blanks in the machine, the relative positions of said stop and pull-out roll being such that when the advancing end of a blank is in contact with said stop its opposite end will rest in contact with the surface of said pull-out roll proximate said stop, rotation of said pull-out roll operating to flick the contacting end of said blank to the opposite side of said pull-out roll, an idle ejector roll mounted adjacent said pull-out roll and in such close proximity thereto that said pull-out roll and ejector roll will engage and eject blanks delivered between them, means for delivering blanks fed to the machine between said pull-out roll and ejector roll, and means for imparting movement to said stop in a direction to impel a blank between the ejector rolls.

4. In combination, in a machine for separating blanks, a stop which defines the position of the blanks in the machine, said stop being movably supported, blank separating means, pull-out rolls mounted in position to receive blanks therefrom and to advance them into contact with the stop which defines the position of the blanks in the machine, the relative positions of said stop and pull-out roll being such that when the advancing end of a blank is in contact with said stop its opposite end will rest in contact with the surface of said pull-out roll proximate said stop, rotation of said pull-out roll operating to flick the contacting end of said blank to the opposite side of said pull-out roll, an idle ejector roll mounted adjacent said pull-out roll and in such close proximity thereto that said pull-out roll and ejector roll will engage and eject blanks delivered between them, means for delivering blanks fed to the machine between said pull-out roll and ejector roll; a spring holding said stop in normal position, a star wheel mounted to impart discharge motion to said stop, and means for actuating said star wheel.

5. In combination, in a machine for operating on blanks, a movable stop which defines the position of the blanks in the machine, pull-out rolls mounted in position to advance blanks into contact with said stop and in position to be fed by the opposite side of one of said pull-out rolls, and means for operating said stop to force said blank back into withdrawing engagement with said pull-out roll.

6. The combination as specified in claim 5 in which the stop is held in normal position by a spring, a star-wheel is mounted to impart discharging motion to said stop, and means are provided for actuating said star-wheel.

7. Blank feeding and ejecting means comprising a driven roll, idle rolls at substantially opposite sides thereof adapted to hold blanks passing between said driven roll and idle rolls, respectively, in frictional contact with said driven roll, a stop which defines the position of the blanks, the relative posi-

- tions of said driven roll and stop being such that when the advancing end of a blank rests in contact with said stop, its opposite end will rest in contact with the proximate side of the driven roll, rotation of said driven roll operating to flick the ends of the blanks contacting therewith to the opposite side thereof in position for engagement by said driven roll and the idle roll at the corresponding side thereof, and means for delivering 10 blanks to be ejected between said driven roll and idle roll.
8. Blank feeding and ejecting means as specified in claim 1, in which the stop which defines the position of the blanks is movable, and which comprises means for imparting movement thereto in a direction to deliver 15 a fed blank between the driven roll and idle roll.
9. Blank feeding and ejecting means as specified in claim 1, in which the stop which defines the positions of the blanks is movable, and which comprises a spring which holds said stop in normal position; a star- 20 wheel mounted to impart a discharge movement to said stop, and means for actuating said star-wheel.
10. In a machine for separating and feeding blanks, the combination of a blank receptacle, blank separating means comprising a separator plate which forms the bottom of the blank receptacle, a separator roll mounted in said blank receptacle, means for supporting blanks in edgewise position on 25 the separator plate with the front blank in contact with the separator roll, means for advancing the blanks towards said separator roll, means for imparting rotation to said separator roll, and a gauge plate which extends from a point above the separator roll 30 lengthwise over the blank receptacle in position to engage the upper edges of the blanks contained in said receptacle, operating to hold their lower edges in contact with the 35 separator plate and to support them at desired inclination to the separator plate.
11. In a machine for separating and feeding blanks, the combination of a blank receptacle, blank separating means comprising a separator plate which forms the bottom of the blank receptacle, a separator roll mounted in said blank receptacle, means for supporting blanks in edgewise position on the separator plate with the front blank in 40 contact with the separator roll, means for advancing the blanks towards said separator roll, means for imparting rotation to said separator roll, and a gauge plate which extends from a point above the separator roll 45 lengthwise over the blank receptacle in position to engage the upper edges of the blanks contained in said receptacle operating to hold their lower edges in contact with the separator plate and to support them at a de- 50 sired inclination to the separator plate, said
- gauge plate diverging rearwardly at a slight angle to the separator plate.
12. In a machine for separating and feeding blanks, the combination of a blank receptacle, blank separating means comprising a separator plate which forms the bottom of the blank receptacle, a separator roll mounted in said blank receptacle, means for supporting blanks in edgewise position on the separator plate with the front blank in 55 contact with the separator roll, means for advancing the blanks towards said separator roll, means for imparting rotation to said separator roll, and a gauge plate which extends from a point above the separator roll 60 lengthwise over the blank receptacle in position to engage the upper edges of the blanks contained in said receptacle operating to hold their lower edges in contact with the separator plate and to support them at a de- 65 sired inclination to the separator plate, said
13. In a machine for separating blanks, the combination of a reciprocating member, a pack receptacle mounted thereon constructed 70 and arranged to carry a pack of blanks to be fed, and means carried by said reciprocating member for automatically discharging a blank at each reciprocation.
14. Feeding mechanism as specified in 75 claim 13, in which means are provided whereby the discharging means is operated by the reciprocations of said reciprocating member.
15. Feeding mechanism as specified in 80 claim 13, in which a stationary rack bar is 85 operatively connected with said discharging means for operating the same.
- In witness that I claim the foregoing as my invention I affix my signature this 18th day of July, A. D., 1927.
